PROCESS OF CRACKING OIL.

Application filed November 17, 1924. Serial No. 750,240.

In the processes commonly employed for cracking hydrocarbons, the material is heated to a cracking temperature under pressure, the vapors of the cracked hydrocarbons being driven off and condensed. In the continuous process which is generally favored, fresh material to be cracked is fed into the still during the major portion of the run and during a considerable period thereof tar is drawn off in order to prevent the accumulation of too large a proportion of heavy material. In what is known as the semi-continuous process, fresh oil is fed in during the run, but no tar is drawn off. In both of these methods of operating, the process is carried on only to a point at which the residue in the still remains in a sufficiently fluid condition to be largely drawn off from the still in the liquid state. It has been proposed to carry the process on to the production of dry coke from the residue in the still, but little practical success has been had in the effort to carry this proposal into effect.

Our invention relates to a semi-continuous process in which the residue in the still is reduced to a dry dense coke which can be readily removed from the still at the end of the operation and is suitable for use as domestic fuel and for other purposes for which coke from coke stills is commonly employed. Among the advantages of our improved process is the production of a valuable coke, fuel economy due to the fact that a smaller total amount of oil is heated for a given production of distillate, an increase in the amount of distillate produced from the material treated, an increase in the rate of distillate and gasoline production and an elimination of certain objectionable features of the continuous process which have been experienced in connection with the removal of tar, such as the plugging of the tar lines and coolers. As compared to the semi-continuous operation in which the residuum is reduced only to pitch we have the advantage of the absence of plugged tar lines and coolers from the pumping of batch bottoms and the avoidance of the difficulties and objections incident to the handling of pitch, among which may be mentioned the difficulty and delay in cooling due

to the difficulty of extracting the heat from the non-porous pitch. We have the advantages also in our process that no vapor or pitch pockets are formed which are liable to flash during the cleaning of the still, the greater ease of handling and removing coke rather than pitch and the value of the coke on the market.

In our improved process, after the bulk of the volatiles have been driven off and the residue approaches the condition of coke, we gradually lower the operating pressure to 40 pounds or so, thus promoting the vaporization of the pitch constituents and also introduce a substance in a gaseous or vapor state which reduces the partial pressure of the pitch and therefore facilitates its vaporization. The components of the pitch are driven off in the order of their gravities as the pressure is lowered so that when it is down to 40 pounds all of the heat is available for vaporizing the heaviest components. Preferably, the introduced substance is pre-heated to a temperature above the normal cracking temperature employed in the still so that additional heat is supplied to maintain a temperature sufficient to both vaporize and decompose the pitch constituents. In our improved process, the introduced substance in question is so supplied as to permeate the entire charge in the shell and preferably it is introduced at the bottom thereof so that in passing upwardly through the coke it serves as a carrier to assist in the removal of the heavier vapors. Other features and advantages of our process will be understood from the more specific disclosure thereof in connection with the drawing accompanying and forming a part of this specification.

The drawing is diagrammatic and represents a suitable apparatus for carrying out our process partly in elevation and partly in section.

Referring now to the drawing, 1 is a shell into which is charged the oil to be treated. We have found it satisfactory not to directly heat the shell, though it may be gently heated without departing from our invention. We have shown no direct heating means however. The oil is heated by a heating medium.

injected into the body thereof as will presently be described. Manholes 2-2 are provided for the removal of coke at the end of the operation or run and an emergency 5 draw-off 3 is provided in case for any reason it may be necessary to remove the residuum in the liquid condition. The vapors from the still are carried through a line 4 to a reflux condenser or heat interchanger 5 in which 10 the vapors of the heavier hydrocarbons are condensed. The disposal of the condensate will be presently described. From the condenser 5, the lighter vapors and gas are conducted by a line 6 to a second heat inter- 15 changer 7 in which a further condensation of vapors takes place and from which the lighter vapors including the desired distillate and incondensable gases are led by pipe 8 to a condenser and receiver. The latter may be 20 of the well-known types employed in connection with cracking stills and provided with the necessary valves for pressure control.

After the proper charge has been introduced into the shell 1 in heated condition in 25 the manner hereinafter described it is maintained at a cracking temperature by the injection thereinto of lighter hydrocarbons in the form of gas or vapor. For this purpose, relatively light oil, which may be gas oil, 30 is fed from a suitable source 9 through a superheater 10 in which it is vaporized before being injected into the still 1. From the supply 9, the lighter oil passes through a pipe 11, meter 12 and valve 13 to a pump 14 by 35 which it is forced through pipe 15 into the heating coil 16. The heating coil is maintained at a temperature considerably above the cracking point so that the oil fed therethrough is vaporized and more or less 40 cracked. The particular construction of the heater 10 is not essential, but I have shown it as comprising baffle passages with a fire box and burner 17 located at the upper end of the passage through which the coil ex- 45 tends, the outlet flue 18 being at the bottom or lower end of the heating flue. The arrangement of the coil 16 is such that in its passage therethrough the oil is subjected to an increasing temperature. If desired, more or 50 less of the partially cooled products of combustion may be re-cycled through the bypass 19 into the fire box to moderate the temperature of the freshly formed products of combustion.

55 From the heating coil 16, the oil vapors are led through a pipe 20 to a system of perforated pipes 21 adjacent the bottom of the shell 1. The pipe 20 is provided with a check valve 22 to prevent the flow of the oil from 60 the shell 1 back to the heating coil 16 in case anything should go wrong. Instead of pumping the light oil directly into the coil 16, it may be preheated in the heat interchanger 7 by the vapors given off from the still. For 65 this purpose, we have provided a pipe 23

leading from pipe 15 to one of the chambers of the heat interchanger 7 and a return pipe 24 is also connected to the feed pipe 15. Valves 25, 26 and 27 are provided in these pipes for the control of the flow therethrough. 70 When it is not desired to preheat the light oil, the valve 25 is opened and the valves 26, 27 closed, but when the oil is to be preheated valve 25 is closed and valves 26, 27 opened.

The light oil fed from the reservoir 9 is or 75 may be supplemented, after the still is in operation, by reflux condensate from the heat interchangers 5 and 7. For this purpose, branch pipes 28, 29 are connected to the vapor or condensing chambers of the respective 80 heat interchangers and are also connected to a common pipe 30 by which the reflux is connected to a reservoir 31. From the latter the reflux condensate may be drawn as required or desired through pipe 32 and valve 33 lead- 85 ing to the inlet side of pump 13. Thus, the reflux condensate may be mixed with the light oil coming from reservoir 9 or used alone to feed the coil 16.

Preferably, the heavy oil, which may be 90 reduced crude, is preheated during the run before being injected into the still 1. For this purpose, the heavy oil reservoir 34 is connected to a pump 35 by which it is forced through a meter 36 and line 37 to the liquid 95 space of the reflux condenser or heat inter- 100 changer 5. From the latter, the oil after being preheated flows through pipe 38 into the perforated pipe 39 in the vapor space of the still shell.

The charge of heavy oil with which operation is started is introduced into the shell 1 through the coil 16 in which it is heated, preferably to a temperature approaching its cracking point. A quantity of oil may be 105 thus fed sufficient to half fill the shell. The feed of light oil through the coil 16 is then begun, the firing of the heater 10 being continued. The vapors of the lighter oil from coil 16 are distributed in the lower part of 110 the heavy oil in the still and rapidly heat the latter. When the desired cracking temperature is reached, the feed of additional heavy oil is begun and is continued together with the feed of the lighter oil and reflux through 115 the coil 16 during the major portion of the run. The feed of heavy oil is then discontinued, but the feed of light oil continued for a further shorter period, the pressure in 120 the still being slowly reduced from the 95 pounds normally employed to about 40 pounds to facilitate the vaporization of the heavy oil remaining in the residuum. As the coke in the shell approaches dryness, the feed 125 of light oil through the heater 16 into the shell is discontinued and steam is introduced in its stead. The feed pipe 15 is provided at 40 with a steam connection to a suitable source of supply under pressure. For a portion 130 of the time during which steam is intro-

duced, the furnace 10 is fired so that it is superheated to a temperature materially higher than the cracking temperature in the shell 1. The steam is superheated in the coil 5 16 and being injected into the bottom of the shell 1 through perforated pipe or pipes 21 thoroughly permeates the coke and heats and assists in carrying off the vapors of the heavy oil remaining in the coke. After the coke 10 is sufficiently freed of liquid hydrocarbons, the fire in the furnace 10 is shut off and the feed of steam continued which cools off the furnace 10 and also the shell 1 and its contents.

15 We will now describe a run on the apparatus disclosed above, exemplifying the practice of our invention:

The shell was charged with 9050 gallons of reduced crude oil (oil from which the lighter 20 ends had been distilled off) through the coil 16 in which it was heated to a temperature somewhat below that at which it would begin to crack. Gas oil was pumped into the heating coil and injected into the body of oil in the shell at a temperature of about 950 25 degrees F. and in the condition of a vapor. The body of oil was heated to cracking temperature and 95 pounds pressure was reached in 8 1/4 hours. Communication to the condenser was then opened in the usual manner and operation was continued for 38 1/4 hours while feeding an average of 975 gallons of gas oil per hour. The gas oil in this and the preceding part of the run was heated to a 30 temperature of about 950 degrees F. in the coil of the heater and vaporized, and the vapor injected through the perforated pipe or pipes 21 into the body of oil in the shell maintained the latter and the infed oil at a 35 cracking temperature between 720 and 750 degrees F. During this on-stream period additional reduced crude was fed to the shell at a rate of about 550 gallons per hour. It was preheated by passing through the liquid 40 space of the reflux tower 5 to a temperature of about 590 degrees F. on its way to the distributing spider 39 in the vapor space of the shell. After the still had been on-stream for 45 32 hours the feed of reduced crude was terminated and the pressure reduced in the course of two hours from 95 pounds to 40 pounds. During this portion of the run the feed of gas oil from the source 9 and of reflux distillate from the receiver 31 was 50 continued but at a lower rate than that at which distillate was being taken off. The still was run for four hours at 40 pounds pressure, feeding gas oil through the heater at 950 degrees F. during this period to decompose and 55 distill the pitch content of the still charge, this operation being facilitated, as heretofore stated, by the reduction in pressure. At the end of this period the coke in the still was dry as is shown by a rise in temperature, 60 from the initial temperature at which pres-

sure reduction was started (750 degrees F.) to a temperature of 830 degrees F. after the still had been on-stream a total of 38 1/4 hours.

The oil feed through the heater was then shut off and steam introduced through the 70 heater, (which was still being fired) superheating the steam to a temperature of 1000 degrees F. By thus introducing superheated steam into the body of coke and beneath the free surface thereof the temperature of the 75 shell content was further raised and the partial pressure of the steam promoted the vaporization of the heavier oil remaining in the coke. The introduction of superheated steam was continued for a period of six hours, after 80 which the fire was shut off but the introduction of steam continued, thus cooling off the heater and still. The saturated steam supplied at this time was passed through the tower and condenser to a slop tank. Eight 85 hours after the fire was off the still was opened. The coke bed was found to be dry and dense but porous in every direction with no pitchy content. Water was sprayed on the coke to cool it, after which it was readily removed from the shell. During the operation of the still 37260 gallons of gas oil were fed through the heater to the still, and 21150 gallons of reduced crude were fed to the shell. 90 98.3 per cent of distillate of the total feed of heavy oil was produced. 23250 pounds of coke were obtained from the shell of a quality fully equal to the coke properly made in the conventional direct fired coke still.

The introduction of the vapors of lighter oil and later of steam creates a partial pressure which facilitates vaporization in the shell. Moreover, the introduction of the lighter vapors and the cracking thereof which takes place after coke has been formed 100 deposits carbon in the interstices of the coke bed, thus producing a dense and firm coke but which is nevertheless readily removed from the shell. By introducing the vapors, 105 whether of oil or water or other substance into and throughout the body of coke, they also serve as a carrier assisting in the removal of heavier vapors as they are formed. As all the oil fed to the still, except the residue thereof in the form of coke, appears as distillate the process is an efficient one both with 110 respect to the percentage of distillate obtained and the amount of fuel consumed. The coke is of such high grade that it forms 115 a valuable by-product. Obviously, in place of superheated steam some other gaseous material or material in the form of vapor may be used.

We claim:

1. A process of cracking heavy hydrocarbons for the production of lighter hydrocarbons and coke, which comprises heating an externally unheated body of the oil to be cracked to a cracking temperature under pressure and distilling off the cracked hydro- 120 125 130

carbons as formed by injecting into said body vapors of hydrocarbons at a temperature above the cracking point, and thereafter injecting superheated steam into the residuum beneath the free surface thereof while discontinuing the injection of hydrocarbon vapors.

2. A process of cracking heavy hydrocarbons for the production of lighter hydrocarbons and coke, consisting in heating a body of the oil to be treated to a cracking temperature under pressure and distilling off the cracked hydrocarbons formed without the direct application of heat to said body by injecting thereinto vapors of a lighter oil heated to a temperature above the cracking point, and thereafter injecting superheated steam into the residuum beneath the free surface thereof while discontinuing the injection of lighter oil vapors.

3. A process of cracking heavy hydrocarbons for the production of lighter hydrocarbons and coke, consisting in heating a body of oil to be treated to a cracking temperature under pressure and distilling off the cracked hydrocarbons formed without the direct application of heat to said body by injecting thereinto vapors of lighter hydrocarbons heated to a temperature above their cracking point, and thereafter injecting into the residuum a gas heated to a temperature above the vaporizing point of the liquid components of the residuum while discontinuing the injection of lighter hydrocarbon vapors.

35 4. A process of cracking heavy hydrocarbons for the production of lighter hydrocarbons and coke, which consists in maintaining a body of oil to be cracked at a cracking temperature under pressure by injecting thereinto beneath the free surface thereof vapors of hydrocarbons heated above the cracking temperature, thereafter injecting into said body a gas heated to a temperature above the vaporizing point of any hydrocarbons remaining therein while discontinuing the injection of hydrocarbon vapors, and continuing the injection of said heated gas until the residuum becomes substantially dry coke.

5. A process of cracking heavy hydrocarbons for the production of lighter hydrocarbons and coke, which comprises maintaining a body of oil to be cracked at a cracking temperature under pressure by injecting into said body beneath the free surface thereof vapors of hydrocarbons at a temperature above the cracking point, feeding additional quantities of heavy oil to said body of oil during a portion of the period when said vapors of hydrocarbons are being injected thereinto, discontinuing the supply of heavy oil and hot hydrocarbon vapors to said body, and further heating the residuum from said body by injecting thereinto beneath the free surface thereof a gas heated to a temperature substantially above the vaporization point of the

heaviest liquid component of said body, and continuing such further heating until the residuum is reduced substantially to dry coke.

6. A process of cracking heavy hydrocarbons for the production of lighter hydrocarbons and coke, which comprises heating the oil to be cracked to a cracking temperature under pressure and distilling off cracked hydrocarbons as formed by injecting into said oil vapors of hydrocarbons at a temperature above the cracking point, reducing the pressure on said oil while continuing the feed of vapors, and thereafter injecting a gaseous medium at a temperature above the vaporizing temperature of the heaviest hydrocarbon remaining in the residue while discontinuing the feed of vapors.

7. A process of cracking heavy hydrocarbons for the production of lighter hydrocarbons and coke, which comprises heating a heavy oil to be cracked to a cracking temperature while maintaining thereon a pressure sufficient to prevent substantial distillation of uncracked components thereof, injecting into said oil vapors of hydrocarbons at a temperature above the cracking point, gradually lowering the pressure on said oil while continuing the injection of said vapors, and thereafter injecting a gaseous medium heated to a high temperature to drive off any liquid remaining in the residuum while discontinuing the injection of said vapors.

8. A process of cracking heavy hydrocarbons for the production of lighter hydrocarbons and coke, which comprises heating heavy oil to a cracking temperature under a pressure sufficient to maintain the uncracked oil substantially in liquid condition, injecting into said oil vapors of lighter hydrocarbons at a temperature above the cracking point, lowering the still pressure to about 40 pounds, and thereafter injecting a gaseous medium while discontinuing the injection of hydrocarbon vapors, whereby all liquid components of the residuum are driven off.

9. A process of cracking heavy hydrocarbons for the production of lighter hydrocarbons and coke, comprising heating a liquid body of the heavy hydrocarbons under pressure, conveying a restricted stream of lighter hydrocarbons through a heating zone and supplying heat to vaporize and crack said lighter hydrocarbons during their passage therethrough, maintaining the said liquid body above the cracking temperature by injecting hot vapors of the lighter hydrocarbons thereinto below the free surface of said body and driving off the cracked vapors therefrom, subjecting the vapors driven off to a refluxing operation and returning condensate from the said refluxing operation to the stream of lighter hydrocarbons in the heating zone, thereafter injecting into said liquid body a gas heated to a temperature above the vaporizing point of any liquid hy-

drocarbons remaining therein while discontinuing the injection of hydrocarbon vapors until the residuum becomes substantially dry coke.

- 5 10. A process of cracking heavy hydrocarbons for the production of lighter hydrocarbons and coke, comprising heating a liquid body of the heavy hydrocarbons under pressure, conveying a restricted stream of lighter
- 10 hydrocarbons through a heating zone and supplying heat to vaporize and crack said lighter hydrocarbons during their passage therethrough, maintaining the said liquid body above the cracking temperature by
- 15 injecting hot vapors of the lighter hydrocarbons thereinto below the free surface of said body, reducing the pressure on said liquid body while continuing the feed of vapors, thereafter injecting into said liquid body
- 20 a gas heated to a temperature above the vaporizing temperature of the heaviest liquid components while discontinuing the injection of hydrocarbon vapors whereby all liquid components of the residuum are driven
- 25 off.
